UNITED STATES PATENT OFFICE.

LEWIS C. MYERS, OF BROOKLYN, NEW YORK, ASSIGNEE TO ROYAL TYPEWRITER COMPANY, INC., OF NEW YORK, N. Y., A CORPORATION OF NEW YORK.

TABULATING MECHANISM FOR TYPE-WRITING MACHINES.

1,306,332.

Specification of Letters Patent. Patented June 17, 1919.

Application filed December 3, 1913. Serial No. 265,103.

To all whom it may concern:

Be it known that I, LEWIS C. MYERS, a citizen of the United States, and a resident of the Borough of Brooklyn, in the city of New York, county of Kings, and State of New York, have invented certain new and useful Improvements in Tabulating Mechanism for Type-Writing Machines, of which the following is a specification.

The present invention relates to typewriting machines and particularly to tabulating mechanism associated therewith. The main object and feature of the invention is to provide a so called decimal tabulating mechanism of such construction that its parts can be readily coordinated with the parts of the ordinary tabulating mechanism of existing machines, and therefore can be readily applied to typewriting machines already on the market.

In the accompanying drawings, the invention is disclosed in a concrete and preferred form, in which—

Figure 1 is a vertical, longitudinal sectional view of the well known "Royal" machine, with parts omitted for the sake of clearness, showing the attachment in place.

Fig. 2 is a fragmentary view in front elevation, and with parts broken away, of a bearing attached to the lower front bar of the frame of the machine for supporting the forwardly extending actuating members of the tabulating attachment, and for securing an indicating scale in position on said bar.

Fig. 3 is a vertical sectional view of the parts shown in Fig. 2.

Fig. 4 is a vertical sectional view on the line 4—4 of Fig. 6.

Fig. 5 is a vertical sectional view on the line 5—5 of Fig. 4.

Fig. 6 is a rear elevation partly broken away of the tabulating appliance in position on a typewriting machine, the latter to a great extent indicated diagrammatically.

Fig. 7 is a diagrammatic plan view substantially on the line 7—7 of Fig. 1.

Fig. 8 is an enlarged detail view of the parts shown in the lower right hand corner of Fig. 1.

Fig. 9 is a sectional detail view on line 9—9 of Fig. 1.

Fig. 10 is a detached view in perspective of the casing inclosing the tabulating mechanism.

The framework of the machine is indi-

cated at 3, and 9 is a transversely movable carriage, supporting a platen 20. Suitable carriage escapement means are provided here taking the form of a rack 10 pivotally supported at 10^a on the carriage and normally held in engagement with escapement pinion 12 by means of spring 11. Mounted on the carriage is also a tabulating bar 14 having one or more adjustable stop members 15. Bar 14 is in the form of a rack, and stop member 15 may be adjusted to occupy any letter space position. The ordinary tabulating stop is here in the form of a member 16 pivotally supported intermediate its ends on a bracket 17 and having its end 39 connected by means of link 40 and arms 40^a and 40^b to tabulating key 18. Spring 44 normally keeps stop 16 out of the path of 15. 13 is a carriage releasing lever pivotally supported on the framework which when tilted lifts rack 10 out of engagement with pinion 12. Arm 13^a, extending downward from said lever, is adjacent to the lower end 16^a of tabulating stop 16. It will be understood that when key 18 is depressed upper end 16 moves into the path of stop member 15 and lower end of 16 tilts 13 and lifts rack 10 thereby permitting the carriage to move transversely until 15 and 16 engage. 19 indicates the usual keys for printing letters or numbers as will be understood.

21 indicates a plurality or a group of selectively operated tabulating stops constituting a means for obtaining decimal tabulation. As here shown these stops are in the form of levers pivotally supported, independently of each other at a point intermediate their ends, on shaft 22. This shaft is carried by bracket 17 attached to the rear wall of frame of the machine, said bracket having an extension 24 which forms an abutment to receive the thrust of the carriage when it strikes one of the stops 21. It will be observed that the upper free ends 23 of these levers will be in position to directly engage a member 15 on bar 14 when a lever 21 is rocked into its path and that there are no additional elements between 23 and 15. In order to actuate the carriage release mechanism when any of the stops 21 are in tabulating position, here is provided a bail 41 that lies in front of all the levers 21 and is mounted on shaft 22 by means of flanges 41^a, said flanges being connected by means of tie rod 43. It will be seen that 110

when any one of levers 21 moves into tabulating position bail 41 will be moved forward and will engage stop or abutment 42 on tabular stop 16 and will impart a limit movement thereto insufficient to bring it into the path of 15, but sufficient to cause 13 to lift rack 10 out of engagement with pinion 12.

Stop 42 is in the form of an eccentric washer secured by a set screw so that an adjustment may be effected with relation to ends 23 of arms 21. It will also be noted that spring 44 is curved out and in to clear plate 41 and allow access to stop 42.

15 A plate 25 is secured to the rear bottom of the frame 8 by being clamped between the foot pieces 26 and the frame. This plate 25 has slots 27 through which the lower ends 20 of levers 21 pass and are guided. Rods or bars 28 are connected with the lower ends 25 of the levers and pass beneath the machine so as to extend beyond the front of the frame and are there provided with push buttons or heads 29. The rods 28 are pressed forwardly, and stop arms 23 are held away from the tabulating rack by springs 30 connected between collars 100 on the rods and a plate 31 provided with holes 32 that guide and support the rods. Collar 100 is open 30 at the bottom and is over-size with respect to rod 28 and is secured thereto by means of set screw 100^a. In this way the collar may be renewed from rod 28 without disconnecting the latter. Plate 31 is formed at its 35 upper part to seat in the upper central depression 101 on the lower front bar 33 of the frame in front of the bank of keys and is secured to the rear wall of the front bar by screws 34. The top of plate 31 carries 40 a scale 35, preferably held between the top of the plate and bar 33, the top of the plate being slotted and the bar forming a bolster for the scale. The scale is on a strip 36 of suitable material supported by a base 45 strip 37 and covered by a strip of transparent material 38. The strip 36 and its adjuncts 37 and 38 are held in the upper part of plate 35 by the ends of the top of the plate being bent downwardly and then bent 50 under backing 37, as at 46, a portion of 31 also being bent forwardly and downwardly as at 47, Figs. 2 and 3.

Plate 25 carries a stop 102 to limit the rearward movement of the lower end of levers 21, and a second stop 103 to limit the forward movement of said levers. Both of these stops are in the nature of buffers, and the rear stop is adjustable as shown in Fig. 8 by means of slots 104 and set screws 105.

60 106 is a casing inclosing the decimal tabulator mechanism, said casing consisting of a rear wall 107, side extension 108, top extension 109 and foot pieces 110. Foot pieces 110 rest on plate 25 and are secured thereto 65 by bolts 111, and ears 112 of side walls 108

receive rivets or screws 113 that extend into bracket 17 (Fig. 1).

I claim:

1. Tabulating mechanism for typewriting machines comprising: a transversely movable carriage, carriage escapement means, carriage escapement release means, a tabulating stop stationary as regards transverse movement of the carriage, means for projecting said stop into the path of a member 70 on the carriage, means for actuating the carriage escapement release means when so projecting said stop, a group of selectively operated tabulating stops also stationary as regards transverse movement of the carriage, 80 means for selectively projecting one of said groups of stops into the path of a member of the carriage, and means for causing the first-mentioned stop to actuate the carriage escapement release means when projecting any 85 one of the group of selective stops.

2. Tabulating mechanism for typewriting machines comprising: a transversely movable carriage, carriage escapement means, carriage escapement release means, a tabulating 90 stop stationary as regards transverse movement of the carriage, means for projecting said stop into the path of a member on the carriage, means for actuating the carriage escapement release means when so projecting said stop, a group of selectively operated tabulating stops also stationary as regards transverse movement of the carriage, means for selectively projecting one of said groups 95 of stops into the path of a member of the carriage, and means for imparting a limited movement to the first-mentioned stop when projecting any one of the groups of selective stops, said movement being insufficient to bring it into the path of the member on the 100 carriage but sufficient to cause it to actuate the carriage escapement release means.

3. A tabulating attachment applicable to typewriting machines comprising: a group 110 of selectively operated tabulating stops supported on the rear wall of the frame of the machine, actuating members extending under the machine to the front thereof, a scale resting on the lower front bar of the frame, said bar forming a bolster for said scale, and a bearing for said actuating members secured to said bar and holding said scale in position thereon.

4. Tabulating mechanism comprising: A transversely movable carriage, a tabulating 120 bar on said carriage adapted to support a stop member, a tabulating stop pivotally supported on one side of a vertical plane passing through said bar, a group of selectively operated tabulating stops pivotally 125 supported on the other side of a vertical plane passing through said bar, an abutment member on the tabulating stop, and a member intermediate the tabulating stop and the group of stops for transmitting the motion 130

of any one of said group to the abutment member.

5. A tabulating attachment applicable to typewriting machines comprising: a group of selectively operated tabulating stops supported on the rear wall of the frame of the machine, a plate at the lower rear wall of the machine having slots for the lower ends of the tabulating stops, and a casing for the group of stops supported on said plate and secured to the machine.

6. A tabulating attachment applicable to typewriting machines comprising: a group of selectively operated tabulating stops supported on the rear wall of the frame of the machine, a plate at the lower rear wall of the machine having slots for the lower ends of the tabulating stops, a casing, for the group of stops, having rear and side-walls and foot rests, means for securing the foot rests to said plate, and means for securing the side walls to the upper rear frame of the machine.

7. A tabulating attachment applicable to typewriting machines comprising: a group of selectively operated tabulating stop levers supported on the rear wall of the frame of the machine, a plate at the lower rear wall of the machine having slots for the lower ends of the levers, and an adjustable rear stop for the lower ends of said levers carried by said plate.

8. A tabulating attachment applicable to typewriting machines comprising: a group of selectively operated tabulating stop levers supported on the rear wall of the frame of the machine, a plate at the lower rear wall of the machine having slots for the lower ends of the levers, an adjustable rear stop for the lower ends of said levers carried by said plate, and a buffer stop also carried by said plate for limiting the forward movement of the lower ends of the levers.

9. A tabulating attachment applicable to typewriting machines comprising: a group of selectively operated tabulating stop levers supported on the rear wall of the frame of the machine, actuating members extending under the machine to the front thereof, a scale resting on the lower front bar of the machine, said bar forming a bolster for said scale, and a bearing of sheet material for said actuating members having a vertical portion secured to the rear wall of the front bar of

the machine and having a horizontally extending portion covering said scale, the ends of said portion being bent beneath the scale aforesaid.

10. A tabulating attachment applicable to typewriting machines comprising: a group of selectively operated tabulating stop levers supported on the rear wall of the frame of the machine, actuating members extending under the machine to the front thereof, a scale resting on the lower front bar of the machine, said bar forming a bolster for said scale, and a bearing of sheet material for said actuating members having a vertical portion secured to the rear wall of the front bar of the machine and having a horizontally extending portion covering said scale, the ends of said portion being bent beneath the scale aforesaid and said bearing having a further downwardly extending portion substantially parallel to the vertically extending portion.

11. Scale indicating means for decimal tabulators comprising: a lower front bar on the machine in front of the bank of keys, a backing member resting on said front bar, a scale member on said backing member, a translucent covering for said scale member, a sheet material member bent angularly and having a horizontal slotted portion resting on the translucent member the ends of which are bent under the backing member and having a vertical portion secured to the front bar of the machine.

12. Scale indicating means for decimal tabulators comprising: a lower front bar on the machine in front of the bank of keys, a backing member resting on said front bar, a scale member on said backing member, a translucent covering for said scale member, a sheet material member bent angularly and having a horizontal slotted portion resting on the translucent member the ends of which are bent under the backing member and having two vertically and downwardly extending portions one of which is secured to the rear walls of the front bar and the other of which overhangs the strips resting on the front bar adjacent the front wall of the latter.

Signed at the borough of Manhattan, city, county and State of New York, this 2nd day of December, 1918.

LEWIS C. MYERS.
